The broken line showing of the household wrap in a dispensed condition is for illustrative purposes only.

I claim:

The ornamental design for a household wrap dispensing container, as shown and described.
